UNITED STATES PATENT OFFICE

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY

HEEL MACHINE

Application filed September 7, 1926. Serial No. 133,941.

This invention relates to heel machines and is herein illustrated as embodied in a machine capable of performing automatically in sequence the operations of compressing and 50 breasting a heel.

My co-pending application Serial No. 660,750, filed September 4, 1923, now Patent No. 1,790,084, dated Jan. 27, 1931, discloses and claims a practical machine adapted to 10 perform the above stated operations upon heels, and in important respects the present invention may be regarded as in the nature of an improvement upon and development of that disclosed in the said application. It will 15 be manifest, however, as the description proceeds, that certain features of the present invention are not limited in their utility to a machine for performing the particular operations named, but are well suited to their own 20 uses in heel machinery of various types.

One important object of the invention is to increase the certainty and accuracy of operation of machines in which blanks such, for example, as heels are fed automatically to one 25 or more positions where operations are performed on them.

With this object in view an important feature of the invention consists in the provision of blank feeding mechanism comprising feed 30 chains provided with means for positively engaging the side edges of a heel blank. In the illustrated machine the heel blank engaging devices consist of fingers mounted upon the feed chains, and a plurality of pairs of such 35 fingers are shown in the accompanying drawings which illustrate a machine adapted to perform a plurality of operations upon a heel, which must, therefore, be fed to a plurality of operating positions.

40 The fingers are so shaped as to effect a positive engagement with a heel blank and this feature, together with another feature of the invention, consisting in the provision of positive stops which predetermine the limit of 45 feeding movement, insures the accurate and certain deposit of each blank in operating position. Preferably the feed chains are positively driven and a further feature of the invention consists in the provision of yielding 50 mountings for said chains whereby, despite

their positive actuation, the limits of their movement may be positively determined without danger of breakage of the mechanism.

Further features of the invention relate to improved means for positioning, holding, and controlling the movements of the blanks to 55 secure increased accuracy and uniformity in the product.

Many other advantageous features and details of the invention will be best understood 60 and appreciated by reading the following description of one successful, practical embodiment thereof in connection with the accompanying drawings in which:

Fig. 1 is a perspective view, from the front, 65 of the principal operating parts of a machine embodying the invention, with portions broken away to reveal parts which would otherwise be hidden;

Fig. 2 is a front elevation of the machine; 70

Fig. 3 is a perspective view of the machine from the rear;

Fig. 4 is a central vertical section on a plane extending from front to rear of the machine; 75

Fig. 5 is a plan view of part of the blank feeding and positioning mechanism;

Figs. 6, 7 and 8 illustrate details of a clutch through which the feed mechanism is driven;

Fig. 9 is a vertical sectional view of a detail of the feed chain mounting taken on the line IX-IX of Fig. 5; 80

Fig. 10 is an enlarged perspective view showing a portion of the feed chain and the blank engaging fingers; 85

Fig. 11 is a perspective view of a detail of the machine at blank receiving position, and

Figs. 12 and 13 illustrate details of the blank supporting and positioning devices. 90

Referring now to the drawings which, as previously stated, illustrate a machine for performing the two operations of compressing and breasting upon heel blanks, 20 indicates a conventional type of frame similar to those commonly used for commercial heel compressors. A stationary heel seat forming die 22 is supported in the frame 20, being immovably secured in operative position by a bolt 24. 95

The heel seat die co-operates with the usual compressing mold, comprising a breast die 26 and side dies 28, carried by a crosshead 30 which is mounted to reciprocate vertically on suitable guides in the frame 10. Reciprocation of the crosshead is effected by the usual toggle mechanism 32 (see Figs. 3 and 4) operated by a connecting rod 34 from the crank shaft 36 which is the main driving shaft of the machine. Further detailed description of this mechanism is unnecessary, inasmuch as it is already well known in the art.

A feed table 38 (Fig. 10) is provided at the front of the machine and is adjustably secured in a slot 40 (Fig. 1) by a bolt 42. The feed table is provided with a gage 44 against which a heel blank 46 may be placed upon a support 48 in position to be received by the blank feeding mechanism.

20 The blank feeding mechanism comprises a pair of endless feed chains 50 running fore and aft of the machine. At the front of the machine the feed chains are engaged and supported by sprockets secured to the upper ends of the vertical shafts 52 and at the rear of the machine the feed chains engage and are supported by sprockets 54 which rotate idly upon pins 56.

30 The front sprockets, upon the shafts 52, serve to drive the feed chains and are operated by mechanism which will now be described. Secured to the lower end of each shaft 52 is a pinion 58 meshing with an idle pinion 60 which in turn meshes with a gear 62. The 35 two gears 62 mesh with each other, as shown in Fig. 2, with the result that the two shafts 52 are constrained to rotate equally and oppositely. The right-hand gear 62 is integral with a sleeve 64 at the lower end of which is formed a clutch flange 66. The clutch flange 66 is recessed in its lower face, as shown at 68 in Fig. 7, and the sleeve 64 is freely rotatable upon a stationary vertical shaft 70.

40 A disk 72, which is also freely rotatable upon the shaft 70, is provided with a pin 74 adapted to engage in the recess 68 and transmit power from the disk 72 to the gear 62. The recess 68 is sufficiently elongated to permit a considerable amount of lost motion between the disk 72 and the gear 62 when the direction of rotation is reversed.

45 The disk 72 rests upon a flange 76 formed upon the hub 78 of a beveled pinion 80 which is also freely rotatable upon the shaft 70. A shear pin 82 provides a driving connection between the flange 76 and the disk 72 but is sufficiently weak to be broken before any damage is done to the mechanism if any interference is encountered in the feeding of the blanks.

50 The pinion 80 meshes with, and is driven by, a beveled gear 84 upon a shaft 86 to which is also secured a gear 88. The gear 88 meshes with a gear segment 90 which is mounted to oscillate about a pivot 92 in a bracket 94

which is carried by the vertically movable crosshead 30, as is also all the mechanism above described. The lower end of the segment arm 96 is pivoted at 98 to one end of a link 100, the other end of which is pivoted at 102 to a stationary bracket 104 secured to the frame of the machine.

55 By following through the mechanism above described, it will be seen that when the crosshead 30 is reciprocated vertically the feed chains 50 will also be reciprocated forwardly and rearwardly of the machine, the rearward, or feeding, movement of the chains occurring during the descent of the crosshead and the forward, or return, movement of the chains occurring during the rise of the cross head. By reason of the lost motion resulting from movement of the pin 74 in the recess 68 there will be a substantial dwell after each reversal of the driving gears, that is to say, before the beginning of the feeding and return movements of the feed chains, the action of the feed mechanism, therefore, being intermittent.

60 In the inner stretch of each chain there is a long link 106 (Figs. 1, 5 and 10) which carries the blank edge engaging fingers, of which there are two pairs. These fingers are so formed as to embrace the side edges of a heel blank and to extend around the breast corners of the blank so that the blank is held and fed positively.

65 Each of the fingers 108 of the front pair is attached to the link 106 unyieldingly in the direction of feed by an easily removable pin 110 which may be inserted in any one of several holes 112 in the link, thus providing for different final positions of the fingers 108 even though the limit of feeding movement of the chains may always be the same. The purpose of this provision is to position accurately heel blanks of different sizes at the same definite position in the compressing mold. The fingers 114 of the rear pair are formed similarly to the fingers 108 of the front pair. Each of the fingers 114 is secured by a readily removable pin 116 (Fig. 5) to an arm 118 which is pivoted at 120 to the corresponding link 106. A small compression spring 122 tends to keep the arms 118 in the position shown in Fig. 5.

70 The function of the fingers 108 is to feed a blank from receiving position upon the support 48 to the compressing mold, and that of the fingers 114 is to feed a compressed blank from the compressing mold to a blank support 124 where another operation, in the present instance breasting, is performed upon it. The space between the fingers 108 and 114 is the same as that between the two mechanisms for operating upon the blank so that, with one rearward movement of the feed chains, one blank is fed from receiving position at the front of the machine to the compressing mold and a previously com-

pressed blank is simultaneously fed from the compressing mold to the blank support 124 where it is to be breasted. In the illustrated machine, for example, the space between that portion of one of the fingers 114 which engages the breast corner of a blank and the corresponding portion of the finger 108 upon the same feed chain is substantially the same as the space between the blank breasting knife and the breast end of the blank compressing mold.

In order that the blanks may be grasped and released by the feeding fingers at the proper times, provision is made for moving the fed chains toward and from each other in proper timed relation to their forward and rearward movements. To this end the front feed-chain sprockets are carried by arms 126, 128 which are mounted to swing about the vertical axes of the respective gears 62, and the rear sprockets 54 are supported in forks 130 mounted upon the outer ends of arms 132 mounted to swing about vertical axes defined by screws 134 which are visible in Figs. 5 and 12. The arms 126, 128 are connected to equal and opposite movements by segmental gears 136 (Fig. 2) and the arms 132 are similarly connected by segmental gears 138 (Figs. 4 and 12).

The approaching and separating movements of the feed chains are derived from a cam 140 mounted upon the driving shaft 36 (see Fig. 3). A cam lever 142 is mounted for movement about a stationary pivot 144 and has at its lower end a cam roll 146 which is held in engagement with the cam 140 by a spring 148. The upper end of the cam lever 142 is connected by a link 150 to a rocker member 152 which is, in turn, connected by a link 154 to an arm 156 which is rigid with one of the arms 132. It will thus be seen that movement of the cam lever 142 by the cam 140 will cause the arms 132, and the sprockets 54 carried thereby, to be moved toward or from each other.

The approaching or separating movement of the arms 132 is transferred to the arms 126, 128 by mechanism which will now be described. Referring to Fig. 12, an arm 158, integral with one of the arms 132, is pivotally connected to a rod 160 which extends forward through the frame of the machine as shown in Figs. 1 and 2. The rear end of the rod 160 is surrounded by a compression spring 162, which takes up any lost motion in the parts and co-operates with the spring 148 in holding the cam roll 146 against the cam 140. The forward end of the rod 160 is provided with rack teeth which engage an idle pinion 164 meshing with a gear segment 166 upon a rocker arm 168 adjustably connected by a screw 170 to the arm 128. By reason of the above described connections the feed chain supporting arms swing toward and from each other in unison and the chains are kept sub-

stantially parallel. The timing of the cam 140 is such that the feed chains are moved toward each other, to cause the fingers 108 and 114 to engage the respective blanks, before the beginning of the inward, or feeding, movement of the chains. At the end of said feeding movement the chains are moved away from each other, releasing both blanks, and this separated relation of the chains is maintained while the blank engaging fingers return to their initial blank receiving positions.

Between the front and rear sprockets the feed chains are supported and guided by bars 172. Each of the long links 106 is provided with a lug 174 which is arranged to engage positively an adjustable stop 176 which definitely determines the inward limit of the feeding movement. Inasmuch as the gearing for driving the chains is positively actuated, always by the same amount, it will be apparent that provision should be made for preventing breakage in the event that the lugs 174 engage the stops 176 before movement of the gearing ceases. This is accomplished by providing yielding mountings for the rear sprockets, which arrangement is effective for the reason that the inward, or feeding, movement of the inside stretches of the feed chains is produced by exerting a forward pull upon the outer stretches of the chains.

Referring to Figs. 5 and 9, there is mounted in the rear end of each bar 172 a housing 178 containing a compression spring 180 which bears against a bushing 182 held upon a rod 184 by nuts 186. The rod 184 is slidable through the housing 178, against the tension of the spring 180. The front end of the rod 184 is provided with an eye through which the pin 56 passes and the bar 172 is slotted at 188 to permit movement of the pin 56 longitudinally of the bar. This construction permits the sprocket 54 to yield forwardly of the machine when the pull upon the outer stretch of the feed chain continues after the lug 174 has engaged the stop 176 and the mechanism is so designed that this action shall always occur, with any adjustment of the stop 176, in order that there shall be no uncertainty as to the completion of the feeding movement.

Stops 190, also engageable by the lugs 174, are arranged to limit the return movement of the feed chains but these stops are solely for the purpose of preventing overthrow of the chains in their return movement, which would be permitted by the lost motion between the pin 74 and the flange 66, and the stops 190 are so positioned that they will not be engaged by the lugs 174 until the shafts 52 cease to rotate.

The blank which is deposited upon the blank support 124 by the fingers 114 is positioned against an adjustable edge gage the details of the construction of which are shown

in Figs. 4, 12 and 13. The heel engaging elements of the back gage consists of two fingers 192 which are guided for transverse adjustment in a dovetail slot 194 formed in an intermediate plate 196 which is guided for fore and aft adjustment in a dovetail slot 198 formed in a base block 200 which has a depending stem 202. Screws 204, threaded in the fingers 192, have unthreaded ends 206 which extend downwardly through transverse slots 208 in the intermediate plate 196 into diagonal slots 210 in the base block 200. The intermediate plate 196 has a downwardly extending ear 212 through which passes freely an adjusting screw 214 which is threaded into the base block 200. It will be understood that, by turning the single adjusting screw 214, the blank edge engaging fingers 192 will be simultaneously adjusted forwardly or rearwardly and toward or from each other, the ratio between the transverse and longitudinal adjustments being determined by the angle between the diagonal slots 210.

The stem 202 is not vertical but is inclined downwardly and rearwardly and is movable in a correspondingly inclined guide 216 formed in the back of the crosshead 30. The inclined stem 202 is retained in the guideway 216 by a plate 218, the fit of the parts being such that there is considerable frictional resistance to up-and-down movement of the stem 202 in the guideway.

At the lower end of the stem 202 there is a rearward projection 220 which is arranged to engage adjustable stops 222, 224 mounted upon a stationary bracket 226. When the crosshead 30 approaches the limit of its upward movement the projection 220 engages the stop 222 and the gage fingers 192 are depressed to, or below, the level of the blank support 124, permitting the blank to be discharged from the gages. When the crosshead approaches the limit of its downward movement the projection 220 engages the stop 224 and the gage fingers 192 are restored to position to be engaged by a blank fed upon the support 124.

In order that a blank upon the support 124 shall be kept under complete control at all times, blank retaining mechanism is provided which engages the blank before it is released by the feed chains and holds it accurately in operating position until the breasting operation has been performed upon it. A blank retainer, consisting of a vertical rod 228, is mounted to move freely through a cross-member 230 (see Figs. 3 and 4) carried by standards 232 secured to, and moving vertically with, the crosshead 30. The rod 228 is connected adjustably to an arm 234 of a bell crank lever which is movable about a stationary pivot 236 and is under the influence of a spring 238 which tends to depress the arm 234 and the blank retainer 228. The other arm 240 of the bell crank lever carries

a cam roll 242 which engages the face of a stationary cam having a vertical portion 244 and an inclined portion 246. There is also provided a vertically movable block 248, depressed by a spring 250, the rear face of which block is a continuation of the vertical portion 244 of the stationary cam. 70

During the downward movement of the crosshead 30 the cam roll 242 rides upon the vertical portion 244 of the cam, including the vertical face of the block 248 which at that time is in the position shown in Fig. 4. The blank retaining rod 228 is thus kept elevated to permit a blank to be fed under it upon the support 124. Near or at the end of the downward movement of the crosshead the roll 242 passes beneath the block 248, permitting the retainer 228 to be depressed by the spring 238 into engagement with a blank which has by this time been fed upon the blank support. As the crosshead 30 rises, the roll 242 carries the block 248 up with it until the roll engages the inclined portion 246 of the cam and is thrown toward the rear until it rides upon the vertical portion 244. 80 90 When the roll is thus moved from beneath the block 248 the latter descends under the influence of the spring 250.

Before the retainer 228 is lifted from the blank, the blank engages a presser foot 252 which is sustained in a stationary friction mounting 254. The friction upon the presser foot 252 is quite heavy and, as the upward movement of the blank support continues, the blank is firmly held while the breasting operation is performed upon it by a stationary breasting knife 256 past which the blank is moved. The chip removed by the breasting knife falls into a chute 258 by which it is conducted away. During the next downward movement of the crosshead 30 the cross-member 230 engages a vertically movable tube 260 resting upon the upper end of the presser foot 252 and acting to restore the said presser foot to its former position, ready to be engaged by the next blank. 100 110

During this downward movement of the crosshead 30, the heel is discharged into a delivery chute 262 by an automatically operated kicker 264, the construction and operation of which is completely described in my former application hereinbefore referred to. 115

Having described the invention, what is claimed as new and desired to be secured by Letters Patent is:

1. A heel machine comprising means for operating upon a heel blank, and a pair of feed chains at opposite sides of the operating means, said feed chains being provided with means for positively engaging the side edges of a heel blank. 125

2. A heel machine comprising means for operating upon a heel blank, a pair of feed chains at opposite sides of the operating

- means, and heel blank side edge engaging fingers mounted upon said feed chains.
3. A heel machine comprising means for operating upon a heel blank, a pair of feed chains at opposite sides of the operating means, and means carried by said chains for simultaneously positively engaging the side edges of a plurality of heel blanks. 70
4. A heel machine comprising means for operating upon a heel blank, a pair of feed chains at opposite sides of the operating means, and a plurality of pairs of heel blank side edge engaging fingers mounted upon said feed chains. 75
- 15 5. In a heel machine, the combination of a plurality of separated mechanisms for operating upon a heel blank, a pair of feed chains arranged at opposite sides of said mechanisms and movable in straight lines from one to another of said mechanisms, and a plurality of pairs of heel blank edge engaging fingers mounted upon said chains and spaced apart the same as said operating mechanisms. 80
- 20 6. In a heel machine, the combination of a compressing mechanism, a breasting mechanism, and blank feeding mechanism comprising a blank engaging device reciprocable between a blank receiving position and compressing position and a blank engaging device reciprocable between compressing position and breasting position. 85
- 25 7. A machine for compressing and breasting heels in a continuous operation having separated, alined, heel receiving, heel compressing, and heel breasting stations, and reciprocating means for feeding heels one at a time from the receiving station to the compressing station and from the compressing station to the breasting station. 90
- 30 8. In a heel machine, the combination of means for operating upon a heel blank, a feed chain for feeding a blank to operating position, and a stop arranged to be engaged by an element of said chain to stop the feeding movement of the chain when a blank reaches operating position. 95
- 35 9. In a heel machine, the combination of means for operating upon a heel blank, a feed chain for feeding a blank to operating position, a stop arranged to be engaged by an element of said chain to stop the feeding movement thereof, and a blank engaging finger mounted upon the chain and adjustable to different positions thereon to provide for the feeding of blanks of different sizes to the same operating position. 100
- 40 10. In a heel machine, the combination of means for operating upon a heel blank, a feed chain for feeding a blank to operating position, and an adjustable stop arranged to be engaged by an element of said chain to stop the feeding movement of the chain when a blank reaches operating position. 105
- 45 11. In a heel machine, the combination of

- means for operating upon a heel blank, a feed chain reciprocable between a blank receiving position and operating position, and stops at said two positions arranged to be engaged by an element of the chain to determine positively the limits of its reciprocating movement. 110
12. In a heel machine, the combination of means for operating upon a heel blank, and means for holding a blank in predetermined operating position, comprising an edge gage deppressible below the blank in an inclined path. 115
13. In a heel machine, the combination of means for operating upon a heel blank, and means for holding the blank in a predetermined operating position, comprising a frictionally supported edge gage deppressible below the blank and mechanical means for raising and lowering said gage. 120
14. In a heel machine, the combination of a reciprocating work support, a frictionally held gage movable from an inoperative position to a position in which it engages a blank upon said support, and means whereby movement of the work support causes movement of said gage between operative and inoperative positions. 125
15. In a heel machine, the combination of means for operating upon a heel blank, a feed chain for feeding a blank to operating position, positive actuating mechanism for said feed chain, a positive stop arranged to be engaged by an element of said chain to determine the limit of its feeding movement, 130 and a yielding mounting for said chain. 135
16. In a heel machine, the combination of means for operating upon a heel blank, an endless feed chain for feeding a blank to operating position, a plurality of sprockets upon which said chain is supported, mechanism for rotating one of said sprockets positively to drive the chain, a yielding mounting for another of said sprockets, and a positive stop arranged to be engaged by an element of said chain to determine the limit of its feeding movement. 140
17. In a heel machine, the combination of means for operating upon a heel blank, a feed chain for feeding a blank to operating position, positive actuating mechanism for said feed chain, positive stops arranged to be engaged by an element of said chain to determine both limits of its feeding movement, and a yielding mounting for said chain. 145
18. In a heel machine, the combination of means for operating upon a heel blank, means for feeding a blank to operating position and releasing it, a blank retainer, means for moving the retainer into engagement with the blank before it is released by the feeding means, and a presser foot, engageable by the blank before it is operated upon, for holding the blank firmly. 150

19. In a heel machine, a vertically movable work support, a blank retainer movable into engagement with a blank upon said support, a tool positioned above the work support, and a frictionally sustained presser foot arranged to be engaged by said blank during movement of the work support toward the tool.
20. In a heel machine, a stationary tool, a heel support movable toward and from the tool, a yielding presser foot sustained in a friction mounting in a position to be engaged by a heel upon the support as the support moves toward the tool, to hold the heel while it is being operated upon by the tool, and a heel retainer movable into engagement with the heel before it engages the presser foot.
21. In a heel machine, a stationary tool, a heel support movable toward and from the tool, a frictionally sustained presser foot positioned to be engaged by a heel upon the support as the support moves toward the tool, to hold the heel while it is being operated upon by the tool, a heel retainer movable into engagement with the heel before it engages the presser foot, and means for returning the presser foot to initial position after the heel has been operated upon.
22. In a heel machine, the combination of means for operating upon a heel blank, intermittent feed mechanism constructed and arranged always to stop at the same point for feeding a blank to operating position, and a blank engaging finger mounted upon said feed mechanism unyieldingly in the direction of feed and adjustable to different positions thereon to provide for feeding blanks of different sizes to and stopping them at, the same definite operating position.
23. In testimony whereof I have signed my name to this specification.

FRED ASHWORTH.
